(21) Appl. No.: **29/261,929**

(57) **CLAIM**

(22) Filed: **Jun. 22, 2006**

The ornamental design for a handle for an arm-mounted video screen, as shown and described.

(51) **LOC (9) Cl.** **08-06**

DESCRIPTION

(52) **U.S. Cl.** **D8/317**

FIG. 1 is a front view of a handle for an arm-mounted video screen showing my new design;

(58) **Field of Classification Search** D8/315–321;

FIG. 2 is a rear view thereof;

D14/239, 134; D6/546–548, 524, 550, 549,

FIG. 3 is a left side view thereof;

D6/518–523, 533, 530; 108/29; 211/27,

FIG. 4 is a right side view thereof;

211/123; 248/175; 16/444, 445

FIG. 5 is a bottom plan view thereof;

See application file for complete search history.

FIG. 6 is a top plan view thereof;

(56) **References Cited**

FIG. 7 is a top left perspective view thereof; and,

U.S. PATENT DOCUMENTS

FIG. 8 is a top left perspective view thereof shown in use condition.

212,881 A * 3/1879 Arnett 16/445

The broken line showing of the mounting portion of the handle in FIGS. 1–7 is included for the purpose of illustrating portions of the handle for an arm-mounted video screen, and the broken line showing of the overhead support bracket and video screen in FIG. 8 is included for illustrating environmental use only and forms no part of the claimed design.
